FLUID HEATER CONTROL

Norman W. Stirling, Plainfield, N. J., assignor
to The Texas Company, New York, N. Y., a
corporation of Delaware

Application April 26, 1934, Serial No. 722,441

2 Claims. (Cl. 196—132)

This invention relates to a control for a fluid heater, and more particularly to a control for a tube still of the type adapted to heat a continuously flowing stream of oil under pressure for cracking or distillation purposes.

It is known to control the operation of a fluid heater or tube still of this type by regulation of the quantity of fuel supplied to the burner or furnace which heats the flowing stream of oil or fluid, by increasing the supply of fuel when the temperature of the flowing stream at a selected point in the path of flow thereof falls below a predetermined value, and decreasing the supply of fuel when the temperature of the flowing stream rises above a predetermined value. In a tube still heater of this type, oil is generally supplied through a heating coil in a continuously flowing stream of small cross sectional area by a pump, which maintains the oil under high pressure, such as from about 50 to 100 pounds per square inch or more, as it flows through the coil. The temperature control mentioned above has been used to maintain the outlet temperature of the oil as it discharges from the heating coil substantially constant at a value depending upon the operation being conducted, and which may be about 600° F. to 900° F. or higher in the case of a cracking or distillation still. In order to maintain such a high outlet temperature of the continuously flowing stream of oil, which is generally passed through the heating coil at high velocity, high furnace temperatures are maintained by the supply of considerable quantities of fuel and air for combustion purposes. Under such conditions, the maintenance of the heating coil in proper operating condition depends upon the continuous supply of oil thereto under pressure and flowing at high velocity to prevent objectionable coke deposition within the tubes due to decomposition of the oil. It sometimes happens that there is a failure of the oil supply, due to a break down of the oil pump or to a failure of the power supply to the prime mover driving the pump, or for other reasons. Should this occur, excessive coking of the tubes of the heating coil usually results, and bulging and splitting of the heater tubes may occur, necessitating a costly shutdown for cleaning or repair.

It is an object of the present invention to provide in conjunction with the temperature control of a fluid heater of this character, a safety control which will automatically terminate the supply of fuel to the burner upon an interruption in the proper supply of oil or other fluid to be heated through the heating coil.

In accordance with the present invention, there is associated with the temperature control which regulates the supply of fuel to the burner, an auxiliary control which is responsive to the pressure of the flowing stream of oil or fluid being heated, and which functions to automatically terminate the supply of fuel to the burner when the pressure of the flowing stream drops below a predetermined minimum. For purposes of illustration, the invention is shown as applied to a tube still heater for oil cracking or distillation; but it is to be understood that the invention is also applicable to other types of fluid heaters.

Referring to the drawing, which illustrates a preferred embodiment of the invention, the single figure is a diagrammatic view of an oil tube still, with the temperature and pressure control of the present invention embodied therein.

The usual furnace of the tube still is indicated at 10, having a heating coil 11 therein, and which may be located in the convection or radiant heating sections, or in both sections, in the customary manner. Any suitable type of tube still or coil heating furnace may be employed. Oil to be heated is drawn from a suitable source of supply through pipe 12 by pump 13 and forced under pressure through line 14 to the heating coil 11. The continuously flowing stream of oil is discharged by line 15 containing valve 16 into a suitable treating chamber 17, which may be a soaking drum or flash distillation chamber or other treating device as is customarily employed with a tube still heater.

Heat is supplied to the furnace of the tube still by a burner 20, to which a suitable fuel, such as gas or fuel oil, is supplied by line 21 from a suitable source of supply. Positioned with line 21 is a control valve 22, which is adapted to regulate the supply of fuel to the burner. Any suitable form of regulating valve or other type of control for the supply of fuel may be employed. That shown is a pressure responsive valve of the balanced type. The stem 23 of the valve is connected to a suitable diaphragm 24 mounted within casing 25, to which a pressure control fluid is supplied above the diaphragm by line 26. A line 27 extends from the line 21 to the casing 25 beneath the diaphragm 24, so that the under side of the diaphragm is responsive to the pressure of fuel being supplied to the burner. A suitable valve controlled bleed 28 is provided for the under side of the diaphragm, and a similar valve controlled bleed 29 is shown for the space above the diaphragm. In the normal functioning of the valve,

the pressure of control fluid from line 26 above the diaphragm is balanced by the pressure of fuel supplied through line 21 and communicated to the space beneath the diaphragm by line 27, so that the valve floats in a partially open position. Any change in pressure of control fluid above the diaphragm temporarily destroys the equilibrium, and is accompanied by a corresponding movement of the diaphragm and valve, whereupon the pressure of the fuel communicated through line 27 is correspondingly changed and the valve regains an equilibrium in its new setting. A by-pass 30 controlled by valve 31 is provided around the regulating valve 22, so that the by-pass can be used when starting up the tube still, communication of valve 22 with the line 21 being then closed by block valves 32 and 33. When the plant has been started and is functioning normally, valve 31 can then be closed and valves 32 and 33 opened, so that the regulating valve 22 is then brought into operation.

Any suitable pressure fluid may be employed for actuating valve 22. As shown, compressed air from a suitable source of supply is passed through line 35 to a liquid trap 36, where condensed liquid or moisture is removed by leg 37, the air then passing by line 38 to a suitable automatic temperature controller indicated at 40. This controller is adapted to regulate the pressure of the control fluid supplied to casing 25 above diaphragm 24 by line 26. The actual pressure of the control fluid in line 26 is regulated in accordance with the temperature of the oil flowing through the coil 11, by a pyrometer 42 positioned adjacent the outlet of the coil 11, and connected to the controller by electrical leads 43 and 44. The controller is set to maintain a predetermined temperature at the outlet of the heating coil. Should the temperature of the oil at this selected point increase beyond the predetermined normal, the controller then functions to decrease the pressure of air or control fluid in line 26, which allows valve 22 to move toward closing position to thereby decrease the supply of fuel to the burner, which restores the temperature of the oil to the desired normal. Conversely, upon a decrease in oil temperature at pyrometer 42 below the predetermined temperature, controller 40 acts to increase the fluid pressure in line 26 and move valve 22 toward fully open position, thereby increasing the supply of fuel to the burner and restoring the temperature of the heated oil to normal. Temperature controllers of this type which function to control the flow or pressure of a fluid in accordance with temperature variation in another fluid being heated are known,—for example, see patent to de Florez No. 1,768,353, dated June 24, 1930. As any suitable conventional type of temperature controller may be employed, no further description of such an instrument is thought necessary. While the controller is shown as responsive to the temperature of the oil adjacent the heater outlet, it is to be understood that it may be made responsive to the temperature of the oil at any other point in its path of flow by a suitable positioning of the pyrometer, or to the temperatures of the oil at several different points in its path of flow by an arrangement of pyrometers connected in series or parallel as is well understood.

Positioned within line 26 is an auxiliary control valve 44, the stem 45 of which is connected to a diaphragm 46 mounted within casing 41. A line 48 extends from the oil supply line 14 on the pressure side of pump 13 to the space above

diaphragm 46, so that the oil pressure normally forces the diaphragm 46 and valve 44 down to fully open position. The pressure responsive valve 41 can be spring loaded by a suitable spring 49 surrounding stem 45 and acting upwardly, so that the valve 44 is closed by the spring when the pressure of the flowing stream of oil within the line 14 falls below a predetermined minimum at which the spring loaded valve is set. The auxiliary pressure responsive valve 41 is thus normally open so that it does not interfere with the supply of control fluid to the fuel valve 22, as regulated by the temperature controller 40. However, should abnormal operating conditions occur in the oil supply line and the pressure drop therein below the predetermined normal, such as would result from a failure of pump 13 or an exhaustion or stoppage of the oil supply from line 12, the resultant decrease in pressure within the oil line will automatically close valve 41 and thus shut off the supply of control fluid to the space above diaphragm 24. The existing pressure beneath the diaphragm will then fully close valve 22 and terminate the supply of fuel to the burner 20. This will rapidly shut down the tube still and thereby prevent injury to the heating coils. The pressure control is thus combined with the temperature control, so that a single control fluid system may be employed, with resultant economy in installation, and reliability in operation.

While the invention has been particularly described in connection with the supply of heat through the regulation of the supply of fuel to a burner, it is of course applicable to the control of heat of an electrical heater, where the pressure control fluid is caused to actuate a suitable switch or rheostat supplying current to the heater as will be readily understood.

Obviously many modifications and variations of the invention, as hereinbefore set forth, may be made without departing from the spirit and scope thereof, and therefore only such limitations should be imposed as are indicated in the appended claims.

I claim:

1. In a fluid heater, having a burner with means for controlling the supply of fuel thereto, a heating coil adapted to be heated by said burner, and a pump for forcing a fluid to be heated through the heating coil in a continuous stream under pressure; a source of control fluid under pressure, a control fluid line connecting said control fluid source to said fuel controlling means whereby said controlling means is actuated in response to the supply of control fluid, regulating means for the supply of said control fluid, thermostatic means responsive to the temperature of the fluid being heated for actuating said regulating means to vary the supply of fuel to said burner in accordance with the temperature of the fluid being heated, and means located between said pump and the outlet of said heating coil responsive to the pressure of said flowing stream of fluid being heated, said last mentioned means being operably connected to the said control fluid line for modifying the supply of said control fluid to the fuel controlling means to thereby entirely cut off the supply of fuel to said burner when the pressure of said flowing stream of fluid drops below a predetermined minimum.

2. In a tube still having a furnace provided with a burner and a fuel line supplying fuel to said burner, a pressure responsive fuel valve for

- controlling the supply of fuel to said burner, a heating coil within said furnace, and a pump for forcing oil in a continuous stream under pressure through said heating coil; a source of supply of control fluid under pressure, a control fluid line connecting said control fluid source to said pressure responsive fuel valve whereby said fuel valve is actuated in response to the pressure of control fluid supplied thereto, regulating means 10 for the supply of control fluid to said valve including thermostatic mechanism responsive to the temperature of the flowing stream of oil adjacent the outlet of said heating coil and adapted to increase or decrease the supply of fuel to said burner upon a decrease or increase respectively 15 in the temperature of the oil, to thereby maintain the oil outlet temperature substantially constant, a pressure responsive valve within said control fluid line, said valve being normally open, and a line from said flowing stream of oil located between said pump and the outlet of said heating coil, said line being operably connected to said last mentioned pressure responsive valve for modifying the supply of said control fluid to the first mentioned pressure responsive fuel valve to thereby entirely cut off the supply of fuel to said burner when the pressure of the flowing stream of oil drops below a predetermined minimum.
